(57) **CLAIM**

The ornamental design for a height adjustable rolling storage cart, as shown and described.

DESCRIPTION

FIG. 1 is a perspective view of height adjustable rolling storage cart of embodiment one;
 FIG. 2 is a front view thereof;
 FIG. 3 is a bottom view thereof;
 FIG. 4 is a top view thereof;
 FIG. 5 is a rear side view thereof;
 FIG. 6 is a left side view thereof;
 FIG. 7 is a right side view thereof;
 FIG. 8 is a perspective view of height adjustable rolling storage cart of embodiment two;
 FIG. 9 is a front view thereof;
 FIG. 10 is a rear side view thereof;
 FIG. 11 is a left side view thereof;
 FIG. 12 is a right side view thereof;
 FIG. 13 is a perspective view of height adjustable rolling storage cart of embodiment three;
 FIG. 14 is a front view thereof;
 FIG. 15 is a rear side view thereof;
 FIG. 16 is a left side view thereof; and,
 FIG. 17 is a right side view thereof.
